(57) CLAIM

The ornamental design for a hand-held pool cleaner, as shown and described.

DESCRIPTION

FIG. 1 is a top, front and left-side perspective view of a hand-held pool cleaner showing our new design;

FIG. 2 is a top, rear and left-side perspective view of FIG. 1;

FIG. 3 is a top plan view of FIG. 1;

FIG. 4 is a right-side elevational view of FIG. 1, the left side being a mirror image;

FIG. 5 is a front elevational view of FIG. 1;

FIG. 6 is a rear elevational view of FIG. 1;

FIG. 7 is a bottom plan view of FIG. 1;

FIG. 8 is a top, front and left-side perspective view of a second embodiment thereof;

FIG. 9 is a top, rear and left-side perspective view of FIG. 8;

FIG. 10 is a top plan view of FIG. 8;

FIG. 11 is a right-side elevational view of FIG. 8, the left side being a mirror image;

FIG. 12 is a front elevational view of FIG. 8;

FIG. 13 is a rear elevational view of FIG. 8;

FIG. 14 is a bottom plan view of FIG. 8;

FIG. 15 is a top, front and left-side perspective view of a third embodiment thereof;

FIG. 16 is a top, rear and left-side perspective view of FIG. 15;

FIG. 17 is a top plan view of FIG. 15;

FIG. 18 is a right-side elevational view of FIG. 15, the left side being a mirror image;

FIG. 19 is a front elevational view of FIG. 15;

FIG. 20 is a rear elevational view of FIG. 15; and,

FIG. 21 is a bottom plan view of FIG. 15.

The broken lines in any of FIGS. 1-21 showing details of the hand-held pool cleaner in dotted lines are for illustrative purposes only and do not form a part of the claimed design.
